John V. Barnes, Attorney.

UNITED STATES PATENT OFFICE.

PEARL V. BARNES, OF SEATTLE, WASHINGTON.

SLEEPING-BAG.

1,241,699.

Specification of Letters Patent.

Patented Oct. 2, 1917.

Application filed January 26, 1916. Serial No. 74,379.

To all whom it may concern:

Be it known that I, PEARL V. BARNES, a citizen of the United States, residing at Seattle, in the county of King and State of Washington, have invented certain new and useful Improvements in Sleeping-Bags, of which the following is a specification.

This invention relates to sleeping bags designed for use by infants and invalids and has as its object to provide an article of this class possessing certain structural features which will insure comfort and retention of the infant or patient occupying the same in a comfortable and yet proper position in the bed and yet permit of the desired freedom of movement of the limbs.

It is one aim of the invention to provide novel means whereby the bag may be connected with the bedding in such manner that it will be retained in substantially the position in which it is initially placed, such means being, however, so arranged as not to interfere with freedom of movement of the body or limbs.

It is another aim of the invention to provide means whereby the bag may be connected with the bed in such manner as to prevent the covers being thrown down.

Another aim of the invention is to so construct the bag that the same may be employed in connection with an ordinary bedstead, in case the bag is to be used by an infant or child, and in such manner as to allow freedom of movement and yet insure the same safety as though the child were placed in a crib.

Another aim of the invention is to so construct the bag that whenever so desired the feet of the occupant may be completely exposed so as to permit of the application of a hot water bottle or the employment of other treatment without, however, having to disarrange the bag or to turn the same back upon the occupant.

In the accompanying drawings:

Figure 1 is a perspective view illustrating the bag in use.

Fig. 2 is a perspective view of the bag.

Fig. 3 is a vertical front to rear sectional view therethrough.

The sleeping bag embodying the present invention may be made up of any suitable material and lined or unlined as desired and the same embodies a front indicated by the numeral 1 and a back indicated by the numeral 2. The bag in general outline is ap-

proximately rectangular although the upper portion thereof is rounded to more or less conform to the outline of the shoulders and the said front and back are united at their margins by a seam indicated at 3. These portions 1 and 2, however, are left ununited at the bottom of the bag and also at the top so as in the latter instance to afford a neck opening indicated by the numeral 4, and the said front and back at this opening are provided with a hem 5 through which is inserted a draw-string indicated by the numeral 6, which string may be drawn sufficiently tight to fit about the neck of the infant or invalid occupying the bag so as to encircle the neck in a comfortable manner and yet exclude drafts. While the bag is herein illustrated as provided with a well defined neck opening which may be more or less restricted by the draw-string 6, it will be understood that the entire upper portion of the bag may be left open if desired or, in other words, the front and back thereof may be left ununited and the draw-string may be employed in the same manner as illustrated in the drawings.

Inasmuch as means, which will herein-after be described, are provided for attaching the bag to the bed covering so that the covering cannot be thrown back, the bag is provided with arm holes indicated by the numeral 7 which permit of perfect freedom of movement of the arms although the arms are protected from drafts by the bed covering, and these arm holes are, of course, provided in the front 1 of the bag and are suitably spaced with relation to the neck opening 4.

In order that the sleeping bag may be so connected or attached to the bed covering as to prevent the covering being thrown back, the front and back of the bag are provided with eyelets indicated by the numeral 8 which are arranged in pairs at opposite sides of the neck opening 4 or, in other words, substantially at the shoulder portions of the bag and attaching tapes 9 are threaded through the eyelets at each side of the bag and each of these tapes is provided at each end with an attaching clip 10 which may be of any suitable construction adapting the same to engage the bed clothing. It will be apparent at this point that the tapes are adjustably threaded through the eyelets and consequently the attaching members 10 of each tape may be both connected to the

bed covering or one of the said devices may be connected to the covering and the other to the under-sheet or mattress or, if desired, to the pillow.

5 In order that the bag may be connected at its sides with the bed covering or the under-sheet or mattress, the bag is provided at each side with a pair of eyelets indicated at 11 and an attaching tape 12 is threaded 10 through these eyelets at its intermediate portion and is provided at its ends with attaching clips or other similar devices indicated by the numeral 13, which clips may be connected as illustrated in Fig. 1 of the 15 drawings, to the under-sheet or mattress or to the bed covering or to both as may be desired. Also, if desired, the tapes 12 may be made of such length as to enable them to be tied about the side rails of the bed frame 20 so as to correctly position the bag within the bed and prevent its displacement.

By reference to Figs. 2 and 3 of the drawings it will be noted that the front 1 of the bag is of less length than the back 2 thereof 25 or, in other words, the front 1 terminates short of the lower edge of the back 2 and the lower portion of the said back is designed to be folded transversely as indicated at 14 so as to afford a flap 15 which

may be detachably connected as by buttons 30 16 or any other suitable means, to the lower edge portion of the front 1 so as to close the lower portion of the bag. It will be understood, however, that while the flap 15 serves the purpose stated, it may be readily opened 35 so as to uncover the feet of the infant or patient, thereby permitting of the application of a hot water bottle or the like without the necessity of inserting the same within the bag proper.

40 Having thus described the invention, what is claimed as new is:

A sleeping bag having a front and a back permanently united along their side edges and along portions of their upper edges, the 45 central portion of their upper edges being ununited to form a neck opening, the front being provided with arm openings at opposite sides of its medial longitudinal line and between said line and its side edges, and the 50 front and back being both provided near each side edge with spaced eyes, a flexible attaching element threaded through the eyes at each edge with its intermediate portion extending between the eyes, and attaching 55 means at both ends of each of said elements.

In testimony whereof I affix my signature.
PEARL V. BARNES. [L.S.]
